UNITED STATES PATENT OFFICE.

DORSEY S. WEBB, OF TRAVERSE CITY, MICHIGAN.

HEATER.

1,086,252.

Specification of Letters Patent.

Patented Feb. 3, 1914.

Application filed March 16, 1912. Serial No. 684,209.

To all whom it may concern:

Be it known that I, DORSEY S. WEBB, a citizen of the United States, residing at Traverse City, in the county of Grand Traverse and State of Michigan, have invented new and useful Improvements in Heaters, of which the following is a specification.

The general object of the invention is to 10 utilize the heat which passes through a chimney for heating rooms; and to this end the invention consists in certain improved constructions, arrangements, and combinations of devices, which will be fully described hereinafter, and then pointed out in the 15 claim.

Other objects will appear and be better understood from that embodiment of my invention of which the following is a specification, reference being had to the accompanying drawings forming part hereof, in which;

Figure 1 is a view partly in side elevation and vertical section of one embodiment of the invention showing it arranged to utilize 25 the heat passing through a chimney which is shown in vertical section, for heating adjacent rooms. Fig. 2 is a front elevation of Fig. 1.

In the drawings *a* indicates the chimney 30 and *b*—*b* the rooms between which the chimney extends vertically. The plates 5—5 are set into openings in the opposite faces of the chimney *a* which are presented to the rooms *b*—*b* and are secured at their upper ends by 35 the angular-shaped flanges 6—6 which extend over the lower faces and inner sides of the bricks at the upper ends of the openings and form benches or supports for the said bricks and those which they support. The 40 flanges 7—7 at the lower ends and opposite sides of the plates 5—5 lap the lower ends and opposite sides of the opening, as shown in Fig. 2.

The radiators 8—8 may be of any preferred contour and they are herein shown to 45 present the appearance of rectangular shaped boxes whose outer faces are preferably but not necessarily plain. The baffles 9—9 in the radiators 8—8 as shown in Fig.

1, are arranged so as to baffle the heated 50 gases and cause them to strike the walls of the radiators during their passage through the same. The radiators 8—8 are suitably connected such as by short tubes 11—11 to flues 10—10 which project outwardly from 55 the middle portions of the plates 5—5 and which communicate with the passage of the chimney through openings 12—12 in the said plates.

The dampers or valves 13—13 control the 60 passage through the chimney and each of the radiators 8—8. When arranged horizontally, the flues 10—10 are open and the passage through the chimney interrupted so that the heated gases rising to the lower 65 dampers are caused thereby to pass through the lower flues 10—10 upwardly through the radiators 8—8, and then through the upper flues 10—10 before they again pass into the chimney *a*. This directing of the gases 70 through the radiators results in the heating of the latter and the consequent heating of the air in the rooms *b*—*b*. When it is desired to heat only one room, for instance the room on the left in Fig. 1, the dampers are 75 turned until they close the openings 12—12. The heated gases now rising through the chimney will strike the lower damper 13 and pass through the radiator and the flues 10—10. When the dampers on the right in 80 Fig. 1 are arranged similarly to those on the left, both radiators will be cut off and the gases passed in the usual manner through the chimney. The damper rods 14—14 which turn the dampers 13 may be of any 85 approved or ordinary construction and arranged so that they may be readily turned to operate the dampers to which they are fixedly secured.

Although I have shown an arrangement, 90 whereby, two rooms may be heated simultaneously by the heated gases passing through a chimney which is located between the rooms, it must be understood that I do not intend to limit myself to this particular 95 arrangement of parts since it will be manifest that the device may be used equally as well with a chimney with which commun-

cation can be made from one room only, in which event, of course, it will be understood that but one radiator will be employed.

What I claim as new is:

5 In a heating apparatus of the class described, the combination of a pair of plates adapted to be arranged in opposite openings in a chimney, radiators arranged in spaced relation to the front faces of said plates, 10 flues directed through said plates and con-

nected to the opposite ends of the radiators, and dampers for controlling the passages through the flues and adapted to coöperate to control the passage through the chimney.

In testimony whereof I affix my signature 15 in presence of two witnesses.

DORSEY S. WEBB.
